Primary Examiner — Paula Allen Greene(57) **CLAIM**

The ornamental design for a neck hanging headphone, as shown and described.

DESCRIPTION

FIG. 1 is a bottom, front, and left side perspective view of a neck hanging headphone showing our new design;

FIG. 2 is a bottom, rear and left side perspective view thereof;

FIG. 3 is a top and front perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof; and,

FIG. 10 is an enlarged view of portion 10 in FIG. 1.

The broken lines in the drawings illustrate portions of the neck hanging headphone which form no part of the claimed design.

The dot dash broken lines in FIG. 1 are for the purpose of illustrating the enlarged view of FIG. 10. The dot dash broken lines form no part of the claimed design.
